US0D1099944S

(12) **United States Design Patent** (10) Patent No.: **US D1,099,944 S**
(45) Date of Patent: ** Oct. 28, 2025

(54) **DISPLAY SCREEN OR PORTION THEREOF WITH GRAPHICAL USER INTERFACE TO VIEW TRADING ORDER FLOW**

(71) Applicant: **Ontario Inc.**, Egbert (CA)

(72) Inventor: **Scott A. Erkkila**, Egbert (CA)

(73) Assignee: **Ontario Inc.**, Egbert (CA)

(**) Term: **15 Years**

(21) Appl. No.: **29/951,629**

(22) Filed: **Jul. 10, 2024**

(51) LOC (15) Cl. **14-04**

(52) U.S. Cl.

USPC **D14/486**

(57) **CLAIM**

The ornamental design for a display screen or portion thereof with graphical user interface to view trading order flow, as shown and described.

DESCRIPTION

The FIGURE is a front view of a display screen or portion thereof with a graphical user interface, according to an embodiment.

The outer broken line rectangle showing the display screen or portion thereof, and all other broken lines showing portions of the graphical user interface, are directed to environment and form no part of the claimed design.
